UNITED STATES PATENT OFFICE.

THOMAS C. SPELLING, OF NEW YORK, N. Y.

NON-REUSABLE BOTTLE AND STOPPER.

1,279,602.

Specification of Letters Patent. Patented Sept. 24, 1918.

Application filed December 28, 1916. Serial No. 139,235.

To all whom it may concern:

Be it known that I, THOMAS C. SPELLING, a citizen of the United States, and resident of the city of New York, in the county of New York and State of New York, have invented certain new and useful Improvements in Non-Reusable Bottles and Stoppers, of which the following is a specification.

10 This invention relates to improvements in bottles and other containers of liquid, though having capacity for a more general use than such use as pertains merely to liquids.

15 The purposes are: to provide (1) a retainer which is non-reusable without its special equipment herein provided, the essential elements in which are destroyed in the first opening of the container; (2) a sealing device one member of which is a form of the stopper now in use, to be of cork or other substance which can be penetrated with a relatively small sharply pointed member with moderate pressure, the other members 25 to be a side stopper of peculiar form, to be formed of any such substance or combination of substances as may be used in the manufacture of artificial stoppers, for instance a compound of corkwood granules and resin or india rubber sap, a pin, preferably of metal, though other hard substance could be used, carrying a flexible clip which in combination mutilates and bisects said side stopper in the act of withdrawal; (3) a 30 locker constructed adaptably to the forms, uses, relations and functions of the parts first mentioned. Its ultimate and more general purpose is the provision of a safeguard against fraudulent substitution, not only of liquids but of other substances.

To facilitate a full and complete understanding of the invention, I will illustrate the preferred embodiment of the same, and the details, arrangement and combination of parts will be learned upon reading the specific description hereinafter set forth in connection with the accompanying drawings, forming a part hereof, wherein said preferred embodiment is illustrated.

50 In the drawings, Figures 1 and 2 are perspective views of opposite sides of my invention, with all parts in place. Fig. 3 is a perspective view of the interior of one side of the neck of a container, as it is to be formed; and Fig. 4 is a perspective view of the interior of the other side. Fig. 5 is a

perspective view, in combination, of the pin and clip to be employed as a fastening means and mutilating agent. Fig. 6 represents the member hereinafter designated as the side stopper, the ordinary stopper being simply designated as the stopper. Fig. 7 is a detached view of the part of the pulling and mutilating member hereinafter designated and described as the clip. Fig. 8 is a perspective view of the member hereinafter designated as the stopper lock, and Fig. 9 is a perspective view of the part hereinafter designated as the pin lock. Fig. 10 is an elevated view of the completed device in place.

Referring more specifically to the drawings, wherein like reference figures designate corresponding parts in the several views, 1 represents that herein designated as the ordinary stopper, and 2 that herein designated as the side-stopper. The reference figure 3 represents a trench formed interiorly in the side of a bottle-neck. It begins at the point where the neck merges, or vanishes in the body portion of the bottle. It is preferably U-shaped, the shell of the neck being correspondingly distended, and terminates with a top opening exteriorly, where a shoulder in the shell of the neck is formed, said shell being gapped in the shoulder to allow the introduction therein and therethrough of a downwardly extended portion, herein designated as the sub-base, of the side stopper. The shoulder and gap therein are represented by the reference figure 4. The general form of the gap is parallelogrammatic, but the space which it opens inwardly is necessarily flared, because of the rotundity of the shell of the neck. At 5 is open space in the shell, formed to admit the inner end of the side-stopper, and above that is another open space 6, formed to allow the emplacement of the stopper-lock. Between said open spaces is a portion of the shell of the neck 25, deflected from the general outline of the shell, as shown in Figs. 3 and 10, in order that the prong 27 of the stopper-lock may be introduced between it and the ordinary stopper and fastened to said intervening portion. When the side-stopper is introduced through said opening 5, its downwardly extended portion, or sub-base 10, is pressed down into the gap 4, and the side-stopper is compressed inwardly by force applied to the pin, and by the act of fastening the latter on the opposite side of the neck,

until its vertically concaved inner end, 7, rests firmly against the ordinary stopper. That portion of it above said downward extension has the two shoulders 9, formed to 5 slide along the top edges of the shell constituting said shoulder on the shell at the top of the trench. Its inner end is vertically shouldered at A to prevent interference by the intervening portion of the neck with its 10 close contact with the ordinary stopper. It is slightly enlarged at 8 in order that the downward pressure of prong 29 of the stopper lock may be intensified, and the downward extension of it will be formed large 15 enough to fit tightly into the gap. That portion of the pin (Fig. 5) between the plate, 13, and the point of contact between the side-stopper and ordinary stopper will be enveloped within the substance of the side- 20 stopper in the process of manufacturing the latter.

The pin will have the head 11, comprising the ring 12, and the plate 13. It will also have the flattened part 14, the slot 15, the 25 sharpened point 16, and the incisions 17. Said slot is a narrow incision in the pin, deep and wide enough to allow the insertion therein of said narrowed portion of the clip. The walls thereof slant at an angle down- 30 wardly from each side and meet at the base. If found necessary the inner or upper walls may be slightly beveled at the tops.

The clip has the middle part 18, the wings 19, the sharp edges 20, the sharp backwardly 35 bent points 21, and the depressed shoulders 22. When incorporated in the side stopper, the middle part of the clip will occupy the slot in the pin, the shoulders, slightly separated from the surface of the pin, will rest 40 within the slightly flattened spaces, 23, in the sides thereof. The wings will rest in angular relation to the pin, and said sharp points will rest near the exterior surfaces at the sides of the side stopper.

45 The stopper lock (Fig. 8), to be constructed preferably of thin sheet metal, will be attached to the portion of the bottle neck adjacent to and above the opening made for the side stopper. It has the loop or bent 50 portion 24 which when in place will inclose said adjacent portion of the neck of the container 25. It has also the correlated holes 26 for rivets, the prong 27, the depending teeth 28, the prong 29 and the box shaped exten- 55 sion 30. For additional fastening means a small buffer having beveled or reduced edges may be inserted in part of the remaining open space above the looped portion of the stopper lock, at 34, said edges extending 60 under the adjacent margins of the neck; and soldering may be used to fill the space above the buffer, said soldering to also envelop said margins. To facilitate said soldering operation, a thin metal slip may be 65 inserted between the stopper and neck, under

said opening, for the protection of the stopper.

Before any of the other parts are put in place, the stopper lock, unriveted will be hooked over said portion 25 of the neck and 70 riveted after all other parts are in place; that is to say, it must be emplaced before the ordinary stopper is inserted, because even a tentative emplacement of the stopper-lock previously might interfere with the inser- 75 tion of the ordinary stopper. Nor should the prongs of the stopper-lock be riveted together until it has been pressed downward into final place, because of resulting interference with the introduction of the side- 80 stopper. Until the other parts of the device are emplaced, the bent portion of the material of which the stopper-lock is formed remains in an elevated position in the open space 6. The last act of assembling is the 85 pressing down of the stopper-lock where- upon the teeth 28 on prong 27 will pene- trate and bind the side-stopper, and the ex- tension 30 of the prong 29 will contact with 90 said enlargement 8 and inclose and impact 95 the sides of the side stopper. The under side of the bent portion, or loop, of the stopper- lock will now rest on the upper edge of said deflected portion 25 of the neck. Next, the rivets are inserted. Said extension 30 is 100 rectangular relatively to said prong 29, and has the general form of a box-lid, minus two sides. The rivets will be inserted through said correlated holes, to firmly unite the prongs, after which the aforementioned, or 105 some other permanent, auxiliary fastening above and on the lock may be resorted to.

It is obvious, the yieldable characteristics of a side-stopper so made being considered, that the sealing effect will be perfected by 105 the coaction of the parts as herein above set forth.

The pin lock (see Fig. 9) has the knob 31 on which are the shoulders 32, to rest, as seen 110 in other figures on the margins of the opening in the shell of the neck on that side. It will also have the hollow extension 33, said 115 hollow to be filled with soldering or other clenching substance, said hollow to inclose the pin point and the incisions thereon the extent of penetration of the pin point there- 120 in to be governed and gaged by the degree of force which is to be applied through the plate to the side-stopper for impacting and tightening the latter. The previously de- scribed method is one practical means for effecting permanent engagement between 125 said neck and pin point, though there may be other and preferable means. The shoulder of the knob will not cover all of said opening in the shell of the neck of the container, and room will be left for the insertion of a nip- per, or other tool to break off the pin-point.

Additionally to their chief functions, the knob and the ring at opposite sides of the 130

neck will be conveniences in handling the container.

When in place the base and depending teeth of the stopper lock will firmly hold the interior end of the side stopper, and it and the clip will coact in bisecting and mutilating the side stopper. Upon the application of pull force at the head of the pin, after the removal of the point at the opposite side, the points and sharp upper edges of the wings will cut or break their ways through the sides of the side stopper, and a continuation of the pull will result in the complete tearing asunder and dismemberment thereof. The fragment held by the teeth and base of the stopper lock may be then otherwise easily removed. In said act of pulling out the pin, the shoulders of the clip will be forced back into contact with the pin and will arrest the backward movement of the wings.

The destruction of the function of the side stopper, of peculiar formation, which would expose any substance which might be thereafter deposited in the container to atmospheric, and other kinds of, contamination through the open trench, would alone afford a safeguard against further or fraudulent use being made of the container, but my invention comprises the additional safeguard involving the destruction, or at least impairment, of the functions of the pin, as above set forth.

Following are the steps taken in assembling: The stopper lock, unriveted, is first loosely emplaced. Then the stopper is inserted. The pull member, carrying the side stopper is next emplaced, the free end of the pin being passed through the stopper until its point emerges in the opening opposite. The stopper lock is then riveted and put in place, as above suggested, and said fastening means above it in said opening inserted. The plate (13) may be then pressed inwardly by the application of pressure on the ring, whereby the side stopper is pressed firmly against the stopper, and the pin-point made accessible at the opposite side of the neck, and the plate alined vertically with the outer edges of the sides of said lock extension. The knob is then attached to the pin point as above indicated.

While I have herein set forth special embodiments of the invention, it is with the realization,—as will appear to persons skilled in the art to which it appertains,—that it is capable of embodiment in other forms and devices, as may be in accordance with the claims appended hereto.

60 I claim:

1. An article of the class described, comprising a bottle having in its neck a vertical interior trench, opening upwardly and outside the normal neck, with corresponding modification of the rotundity of the

neck, a stopper for the ordinary mouth, a side-stopper fitted into a side-opening in the neck and within the top opening of the trench, to constitute, in conjunction with the ordinary stopper, a seal, and means for locking both stoppers in place.

2. An article of the class described, comprising a bottle having in its neck a vertical interior trench, opening upwardly and outside the normal neck, with corresponding modification of the rotundity of the neck, a stopper for the ordinary mouth, a side-stopper, fitted into a side opening in the neck and within the top opening of the trench, to constitute, in conjunction with the ordinary stopper, a seal, and means for locking both stoppers in place, consisting of a retaining pin passed through them, and fastened on the side-stopper and on the neck opposite said side-stopper, the fastening means on said opposite side consisting of a shouldered knob having a hollow extension filled with a gripping substance for enveloping and binding the corrugated point of the pin; also means for bisecting the side-stopper and rendering it useless for the same purpose subsequently, said means consisting of a clip carried by the pin, said clip having two sharp edged and pointed wings and between them a narrowed portion insertible in a slot formed in the pin, said wings enveloped in the substance of the side-stopper and having a plunging and outward movement, resulting from withdrawal of the pin.

3. An article of the class described comprising a bottle having in its neck a vertical interior trench, opening upwardly and outside the normal neck, with corresponding modification of the rotundity of the neck, a stopper for the ordinary mouth, a side-stopper fitted into a side opening in the neck and within the top opening of the trench to constitute, in conjunction with the ordinary stopper, a seal, and means for locking both stoppers in place, consisting of a retaining pin passed through them, secured on the side-stopper, also on the neck opposite said side-stopper with a shouldered knob having a hollow extension filled with a gripping substance for enveloping and binding the corrugated point of the pin; also means for bisecting the side-stopper and rendering it useless for the same purpose subsequently, said means consisting of a pin extending through the side-stopper from end to end and transversely through the stopper in the top mouth and carrying a clip having two sharp edged and pointed wings and between them a narrowed portion insertible in a slot formed in the pin, the portion of the pin connected with the clip and the clip enveloped in the substance of the side-stopper, said clip having a plunging outward movement, resulting from

- withdrawal of the pin, said pin and its said adjuncts coacting with a locking device adapted to impinge the interior end of the side-stopper during the process of withdrawal of the pin, the locking device consisting of a member attached to the neck of the bottle through openings therein and carrying sharply pointed teeth adapted to penetrate, impinge and bind the inner end of the side-stopper, thus giving effect to the bisecting action of the clip member upon the application of pull force to the pin in said act of bisection, as described herein.
4. In an article of the class described comprising a bottle, stopper and locks, a retaining pin passed through a side-stopper from end to end and transversely through the stopper, said pin having engagement against the outer end of the side-stopper through a plate and on the opposite side of the neck in a hollow member filled with a gripping substance adapted to envelop and firmly engage spurs formed on the point of the pin, said hollow member being an extension of a shouldered knob resting on the outer surface of the neck.
5. In an article of the class described, the combination of a bottle, stopper and side-stopper with a retaining pin passed through a side-stopper from end to end and transversely through the stopper, said pin having engagement against the outer end of the side-stopper through a plate, and on the opposite side of the neck in a hollow member filled with a gripping substance adapted to envelop and firmly engage spurs formed on the point of the pin, said hollow member being extended from a shouldered knob through an opening in the shell of the neck.
- 40 6. In an article of the class described, the combination with a bottle and a closure for the bottle comprising a stopper and side-stopper, of means for bisecting and rendering the side-stopper unfit for subsequent use, said means consisting of a clip carried in a slot formed in a pin, said clip having two ends, each end having a sharp point and sharp edges on each side slanting at only a slight angle from the sharp point, a narrow neck connecting the two ends of the clip, and depressed shoulders adapted to engage the pin, upon the application of pull force to the pin, said pin and clip being enveloped in the substance of the side-stopper and adapted to tear apart the two ends of the side-stopper as a result of said application to the pin of pull force.
- 55 7. In an article of the class described, comprising a bottle having in its neck a vertical interior trench opening upwardly and outside the normal neck, with corresponding modification of the rotundity of the neck, a stopper for the ordinary mouth, a side-stopper of yieldable material fitted into a side opening in the neck and within the top opening of the trench, and means for locking the side-stopper in place, the combination with a retaining pin passed through both stoppers and through two opposite openings in the neck of a plate on the end of the pin beyond the side-stopper, adapted to be pressed against and to impact the side-stopper, and simultaneously with the act of so pressing and impacting, to be suitably fastened through the opening on the opposite side of the neck.
8. In an article of the class described, comprising a bottle, stopper and side-stopper, together constituting a seal, and means for interlocking them, a side-stopper shouldered on its lower portion from end to end and on one end vertically, having also a vertical groove in its vertically shouldered end, also an enlargement on its upper side, said side stopper being adapted to be fitted and impacted into an opening in the neck for the bottle and simultaneously into a gap formed in the shell of the neck adjacent to the opening and into the mouth of a vertical interior trench formed in the neck.
9. The combination of a bottle member having a neck in which are a plurality of side openings, and a stopper for a side opening in the neck and a pin for fastening the side-stopper and ordinary stopper through both stoppers and side openings in the neck of the bottle, with a locking and binding fastener for the side stopper consisting of a member bent on and over a portion of the bottle neck left intact between two of the openings therein, said member having two prongs, one to extend downwardly inside said intact portion of the bottle neck, its lower extremity sharply toothed, the other prong to extend downwardly outside said intact portion of the bottle neck, its lower extremity having extension outwardly over the space provided for the side stopper, said extension comprising a top and two side portions for depressing and compressing the side stopper, upon final assemblage and emplacement.

Signed at New York city in the county of New York and State of New York this 7th day of December A. D. 1916.

THOMAS C. SPELLING.
